UNITED STATES PATENT OFFICE.

WILLIAM I. WHEELER, OF SCOTTVILLE, ILLINOIS.

SPEED-CHANGING MECHANISM.

1,421,639.

Specification of Letters Patent.

Patented July 4, 1922.

Application filed February 24, 1920. Serial No. 360,955.

To all whom it may concern:

Be it known that I, WILLIAM I. WHEELER, a citizen of the United States, residing at Scottville, in the county of Macoupin and 5 State of Illinois, have invented certain new and useful Improvements in Speed-Changing Mechanisms, of which the following is a specification, reference being had to the accompanying drawings.

10 This invention relates to certain improvements in speed changing mechanisms, and it is an object of the invention to provide a novel and improved device of this general character wherein pressure is employed to 15 automatically vary the speed of the driven shaft of a motor vehicle in accordance with the engine load.

Another object of the invention is to provide a novel and improved device of this 20 general character embodying a driven shaft operatively engaged with the driving shaft and wherein the driven shaft is provided with means embodying a mobile element to vary the speed of the driven shaft in accordance with the requirements of practice and 25 in a manner obviating the use of gears and which operates automatically.

An additional object of the invention is to provide a device of this general character 30 which embodies a driving shaft operatively connected with the driven shaft and wherein said connection includes a casing rotatably mounted upon the driving shaft and provided with a plurality of cylinders in 35 communication therewith with each of said cylinders in connection with a chamber common to all and which casing, cylinders and chamber are adapted to contain a mobile medium and which structure further embodies novel and improved means for imparting rectilinear movement to the pistons within the cylinders during the rotation of the driving shaft to create the requisite pressure of resistance to vary the speed of the 40 driven shaft in accordance with the engine load.

The invention consists in the details of construction and in the combination and arrangement of the several parts of my improved speed changing mechanism whereby 45 certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in longitudinal section and partly in elevation, illustrating a speed changing mechanism constructed in accordance with an embodiment of my invention;

Figure 2 is a fragmentary view in plan, illustrating the element or member carried by the rod of a piston for co-action with a rotary element to impart the requisite reciprocation to said rod and the piston carried thereby;

Figure 3 is a sectional view taken substantially on the line 3—3 of Figure 1;

Figure 4 is a sectional view taken substantially on the line 4—4 of Figure 1;

Figure 5 is an enlarged fragmentary view partly in section and partly in elevation illustrating in detail the automatic controlling mechanism herein employed;

Figure 6 is a fragmentary sectional view illustrating in detail certain other features comprised in said controlling mechanism;

Figure 7 is a fragmentary view taken in a direction circumferentially of the chamber common to all of the cylinders and through the controlling valve, said controlling valve being shown in full open position;

Figure 8 is a view in perspective of the supporting member for the valve unapplied;

Figure 9 is a view in perspective of the controlling valve as herein embodied unapplied.

As disclosed in the accompanying drawings, D denotes a driving shaft and S denotes a driven shaft in longitudinal alignment with the shaft D. Mounted upon the shaft D is a casing C of requisite dimensions, said shaft D and casing C being capable of independent relative rotation. One end of the casing C is normally open and adapted to be closed by the head or plate H. Carried by the head or plate H and preferably integral therewith is a plurality of cylinders 1, equidistantly spaced in a direction circumferentially of the head or plate H and herein disclosed as four in number. The inner faces of the cylinders

1 are also preferably integrally formed with a block 2, of a length equal to the length of the cylinder 1 and said block 2, at the axial center of the casing C, is provided with a cylindrical chamber 3 having its wall provided with the longitudinally disposed grooves or channels 4. Carried by the driving shaft D and preferably integral therewith is a cylindrical member 5 snugly fitting within the chamber 3. The periphery of the member 5 is provided with a reverse spiral cam channel or groove 6.

15 Mounted for rectilinear movement within each of the cylinders 1 is a piston 7, having operatively engaged therewith the rod 8. The rod 8 is substantially U-shape in form with the outer leg 8^a thereof extending within a groove or channel 4. The free end portion or extremity of said leg 8^a is 20 provided with a laterally disposed part 9 which is seated and rides within the spiral cam channel 6 so that as the driving shaft D rotates, the piston 7 will be caused to reciprocate within its cylinder 1.

25 Each of the pistons 7, as herein disclosed, is of a hollow type and the closed end or head thereof is provided with a port 10 with which coacts a check valve 11, said valve being closed upon the inward thrust of the piston 7 and opening upon the outward thrust. Suitably secured to the outer face of the head or plate H is an annular chamber E in communication, as at 12, with each of the cylinders 1, and said communication is 30 under control of a check valve 14 which is closed upon the outward thrust of the adjacent pistons 7 and open upon its inward thrust.

35 The chamber E is common to all of the cylinders 1 and is also in communication, as at 15, with the casing C and the flow through said connection 15 is under automatic control, as will hereinafter be more particularly referred to.

40 Secured to the outer face of a head or plate H is a housing A having its outer closed end or head 16 freely engaged with the driven shaft S. The drive shaft D extends within said housing A and to said portion of the shaft D is fixed a relatively broad gear 17. Meshing with the gear 17 are the diametrically opposed gears 18. Each of the gears 18 is fixed to a shaft 19 rotatably supported by a carriage 20, supported by the 45 wall of the housing A for sliding movement in a direction longitudinally of the shaft D and the shaft S. The adjacent end of the driven shaft S has affixed thereto a gear 21, preferably of a greater radius than the gear 17. The gear 21 is in mesh with the gears 22, also fixed to the shafts 19. The gearing just referred to is in action at all times and by this means, the driving shaft D is operatively engaged with the driven shaft S and 50 in a manner whereby the driven shaft S may

rotate at varying speeds in accordance with the engine load and which varying speed is under control of the pistons 7 working in the cylinders 1.

55 Each of the carriages 20 is also provided with a relatively broad gear 23 constantly in mesh with a gear 18. When the carriages 20 are moved outwardly to a sufficient extent, the gears 22 disengage from the gear 21 and the gears 23 mesh therewith resulting in a reverse rotation of the shaft S. 24 denotes an actuating mechanism for the carriages 20 and which mechanism may be operated in any desired manner.

60 It is to be understood that when the shaft S is in reverse, a suitable braking means, as indicated at 25, is employed to positively hold the casing C against rotation.

65 In practice, the casing or reservoir C, the cylinders 1 and the chamber E are substantially entirely filled with oil and the circulation of said oil or mobile medium is under control of the valve V. At a predetermined point, a wall of the chamber E is provided with an opening 26 which is closed by a block 27. The block 27 is provided with the marginal flanges 28 overlying the outer face of the adjacent wall of the member E whereby the block 27 may be effectively held in applied position through the 70 instrumentality of the screws 29 or other fastening means. The inner face of the block 27 has extending longitudinally thereof and entirely therethrough a groove or channel 30 substantially semicircular in cross 75 section and the opposite end portions of the block 27 are provided with the inwardly disposed loops 31 having their inner walls or faces also substantially semicircular and in continuity with the groove or channel 30. The block 27 also has directed laterally therethrough and in communication with the groove or channel 30 the ports 32.

80 The valve V is substantially semicircular in cross section and provided at its opposite end portions with the cylindrical parts 33 which are received within the bearings provided by the loops 31. The central portion of the valve V is provided with ports 34 adapted to register with the ports 32 here- 85 before referred to.

85 The ports 32 communicate with a housing 35 suitably secured to the wall of the chamber E. In communication with the housing 35 through the outer wall thereof is the pipe 15 90 hereinbefore referred to.

95 At substantially the center of the convex or rounded face of the valve member V is secured an outstanding pin or shank 36 which is directed through a chamfered opening 37 provided in the block 27. The pin or shank 36 is of a length to extend a desired distance within the housing 35 and terminates in a fork 38. Each of the tines or fingers of the fork 38 is loosely disposed 100

through an opening 40 provided in a poise or weight 41.

The upper and lower walls of the opening 40 are converged in a direction toward the 5 block 27 whereby the requisite relative movement between the poise or weight 41 and the tines or fingers of the fork 38 is permitted. The poise or weight 41 has sliding movement between the guide rods or members 42 interposed between the side walls of the housing 35 whereby said weight or poise 10 41 has movement in substantially a fixed path of travel.

When the driving shaft D is set in motion, the oil is pumped by the pistons 7 into the chamber E through the ports 12 and as the speed of the shaft D increases, the resultant centrifugal force causes the weight or poise 41 to move outwardly, thereby rocking 15 the valve member V, as illustrated in Figure 6, into a position to completely close the ports 32, whereby the circulation of the oil or other fluid medium is stopped and the resistance offered between the pistons 7 and 20 the closed ends of the cylinders 1 drive the casing or reservoir C and the parts carried thereby as a unit with the driving shaft D and whereby the driven shaft is caused to operate direct from the driving shaft.

25 As the load on the engine increases, the resultant reduction in rotation of the casing or reservoir C and its concomitant parts will cause the weight or poise 41 to swing inwardly in accordance with such increase of load, resulting in the ports 34 in the valve member V registering with the ports 32 in the block 27. This movement of the poise or weight 41 is facilitated by the spring or expandible member 43 carried by the upper 30 face of the poise or weight 41. The member 44, as illustrated in Figures 5 and 6, provides means for limiting the extent of registration of the ports 32 and 34 and operates in the manner particularly set forth 35 in my co-pending application, Serial No. 360,954, filed February 24, 1920.

40 From the foregoing description, it is thought to be obvious that a speed changing mechanism constructed in accordance with my invention is particularly well adapted for use by reason of the convenience and facility with which it may be assembled and operated, and it will also be obvious that my invention is susceptible of some 45 change and modification without departing from the principles and spirit thereof, and for this reason I do not wish to be understood as limiting myself to the precise ar-

range ment and formation of the several parts herein shown in carrying out my invention in practice except as hereinafter claimed.

I claim:—

1. In a speed changing mechanism, a driving shaft, a driven shaft, a connection 60 between said driving shaft and driven shaft including a casing mounted upon the driving shaft, said driving shaft and casing being capable of independent relative movement, cylinders arranged within the casing and 65 movable therewith, a chamber in communication with each of the cylinders and the casing, means carried by the driving shaft and positioned within the casing for imparting rectilinear movement to the pistons, 70 each of said pistons being provided with a port affording communication within the cylinder at opposite sides of the piston, said casing, cylinders and chamber being adapted to contain a mobile medium and a single 75 means interposed in the chamber and operating automatically to control the flow of the mobile medium through the chamber and the cylinders.

2. In a speed changing mechanism, a 80 driving shaft, a driven shaft, and means operatively connecting said shafts including a casing mounted upon the driving shaft, said driving shaft and casing being capable of relative independent rotation, cylinders 85 arranged within the casing and movable therewith, pistons movable within the cylinders, a chamber in communication with the casing and each of said cylinders inwardly of its piston, the opposite end of 90 the cylinder being open, said piston being provided with a port affording communication within the cylinder at opposite sides of the piston, a cylindrical member carried by the drive shaft and positioned within the 95 casing, the periphery of said member being provided with a reverse spiral cam channel, a substantially U-shaped rod coacting with each of the pistons, the outer leg of said rod having a part engaged within the channel 100 whereby the piston is reciprocated upon rotation of the drive shaft, said casing, cylinders and chamber being adapted to contain a mobile medium and a single means interposed in the chamber and operating 105 automatically under centrifugal action to control the flow of the mobile medium through the cylinders and the casing.

In testimony whereof I hereunto affix my signature.

WILLIAM I. WHEELER.
